UNITED STATES PATENT OFFICE.

MARKO TUDOROV, OF SAN PEDRO, CALIFORNIA.

COMBINATION LOCK.

Application filed December 31, 1924. Serial No. 759,062.

The invention relates to a key operated combination lock and it is an improvement upon the combination lock shown in my Patent No. 1,355,084.

5 An object of the invention is to produce a strong lock capable of being easily operated, of a very simple construction.

Another object of the invention is to provide a lock mechanism which is applicable 10 to a padlock construction as well as to the ordinary door lock construction; the only difference being that in the case of the padlock a hasp of the usual form is latched within the lock instead of having a projecting lock bar as is the case with the door lock.

15 Other objects of the invention will appear as the description proceeds.

An embodiment of the invention is shown in the accompanying drawings in which the 20 same reference numeral is applied to the same portion throughout, but I am aware that there may be modifications thereof.

Figure 1 is a front elevation of the door lock.

25 Figure 2 is an end elevation of the door lock looking from the right, Figure 1.

Figure 3 is a view of the door lock with the front plate removed.

30 Figure 4 is a sectional view of the door lock on the line 4—4 Fig. 3.

Figure 5 is an edge elevation of the first tumbler.

Figure 6 is a side elevation of the first tumbler.

35 Figure 7 is an edge view of the second tumbler.

Figure 8 is a side elevation of the second tumbler.

40 Figure 9 is an edge elevation of the third tumbler.

Figure 10 is a side elevation of the third tumbler.

45 Figure 11 is a side elevation of the padlock having this combination locking device applied thereto.

Figure 12 is an end view of the padlock looking from the right Fig. 11.

Figure 13 is a sectional view looking from the left Fig. 12 on line 13—13.

50 Figure 14 is a plan view of the middle tumbler.

Figure 15 is a plan view of the No. 3 tumbler.

Figure 16 is a plan view of the latch for securing the padlock hasp in the locked position.

Figure 17 is a plan view of the thin washer used for holding the latch shown in Fig. 16 in the proper place.

Figure 18 is a plan view of the tumbler secured to the key barrel.

Figure 19 is a plan view of a detachable ring with spring retracted plugs to provide means used for operating the lock in the dark.

55 In the form of the invention shown in Figures 1 to 10, the lock consists of an enclosing case 1, rectangular in form, which has the back 2 connected thereto by a series of screws 3 extending into holes 4 to 7 of a shallow flange cast inside the casing 1. On the front of the casing there is the cylinder supporting member 8 which has the flange 9 integral therewith and within which is the key barrel 10. The key barrel may be of any 70 desired form and is operated by the key 11 which has the point 12 to aid in turning the key barrel and the first tumbler 13 which is fastened to the key barrel; screws 14 and 15 being used for the latter purpose. The tumbler 13 has a notch 16 and has a circular groove 17 extending almost entirely around the same; this groove guides a pin 19 which acts to turn the next adjoining tumbler and also acts with its beveled surface 20 to push 75 the lock bolt out to the position shown in Figures 1 and 3 when the beveled surface comes in contact with the beveled surface 21 on the lug 22. The tumbler 13 is secured to the key barrel 10, but the center tumbler 21' and the back tumbler 24 are mounted 80 on a slotted stud 23 secured to the back by the screw 24'. Each of the tumblers 21' and 24 has a shallow central recess to receive an S shaped spring shown at 25, 26 85 to frictionally hold the tumblers in any position in which they may be placed.

90 In order to change the combination the pin 19 may be placed in any one of the series of holes in the tumbler 21', said tumbler 100 also having a rectangular peripheral notch to receive the lug 22.

- The tumbler 24 has a flat spring 27 secured thereto which allows that tumbler to turn counter clockwise Fig. 10 without disturbing either of the other tumblers, but if turned clockwise it will turn the tumbler 21' when the end of the spring strikes the peripheral notch, and if turned more than one turn will turn the tumbler 13 as soon as the pin 19 strikes the end of the slot 17.
- 10 The lock bolt 28 is carried by a rectangular frame 29 which has the lug 22 projecting inwardly and at one end of the frame there is a hole to receive a spiral spring 30 which causes the retraction of the bolt frame whenever the openings in the tumblers 13, 21' and 24 are aligned. When the tumbler openings are aligned the lock frame will snap back to the unlocked position and if the tumbler 13 is turned counterclockwise 20 Fig. 6, it will eject the lug 22 because of the beveled surface 21 and reset the lock. The face of the lock has a suitable dial to facilitate the opening of the lock and operation of the combination.
- 25 The padlock shown in Figs. 11 to 18 has the outer shell 40 with the U shaped hasp 41, the ends of which are slidably in two holes in the casing.
- 30 The long leg of the hasp is notched to allow the locking block 42 to prevent the hasp from being pulled out and to allow it to turn entirely around when at the outer limit of its movement.
- 35 The long leg of the hasp is drilled to receive a pin 43 and spiral spring 44 to throw the hasp outwardly when the tumblers are properly aligned. The short leg of the hasp has a notch 45 to receive the lock member 46 on a flat plate 47. This plate 47 has a central slot which fits over the slotted pin 48, and it also has the lug 49 which is adapted to enter the tumbler slots when they are aligned. This plate 47 is held in place by a thin washer or disk 50 having two screw 45 holes, and the spiral spring 50' tends to push said plate to the unlocked position.
- 40 The tumblers are shown at 52, 53 and 54, Figs. 14, 15 and 18 and they are substantially like the tumblers shown and previously described. The slotted stud 48 has the two S shaped wire springs 54', 55 passing therethrough to steady the movement of the two tumblers 52, 53 which correspond to the tumblers 21', 24.
- 55 The lock shown in Figs. 11 to 18 has its tumblers arranged the same as the other lock, two being on the stud 48 while the tumbler 54 is secured on the key barrel 56 and turns with it.
- 60 The lock barrel 56 is assembled by pushing it into the casing from the right Fig. 13 and it is then secured therein within a shell 56' by the screws which pass through the holes 54'' of the tumbler 54; said tumbler being 65 assembled within the casing from the oppo-

site end through the opening filled by the plate 48' which carried the stud 48 and this plate is in turn held in place by a pin 48''.

In each case the tumblers are aligned by inserting a key in the barrel and turning the key to carry the tumblers 54 and 53 until their notches are properly aligned, then the key is turned back acting to set the middle tumbler, after which a short reverse turn of the key sets the tumbler secured to 70 the key barrel, and allows the lug 49 to drop into all the slots by the action of the spring 50' acting on the plate 47 and withdrawing the lock member 46 from the notch 45 in the hasp 41.

80 In order to provide means for opening the lock in the darkness or at times when the figures cannot be seen, the ring 70 is used to locate the position of the figures. This ring has three unequally placed pins 71, 72, 85 73, which fit the holes 74, 75, 76 in the base of the padlock, whereby the ring must always be placed thereon in a certain position. The ring then has three spring retracted plugs 78, 79, 80, spaced to correspond with 90 the location of the combination numerals so that when one wishes to open his padlock all that is needed is to place the ring on the base of the padlock, insert his key, turning it several times in the proper direction, whereupon the first stop is pressed in with the finger until the key is turned to contract therewith, thereafter this stop is released and the key is turned in the opposite direction, one or more times as may be required, whereupon 95 the next stop is pushed in and the key turned against the same until it stops, thereupon the key may be turned in the opposite direction for the necessary space, whereupon the third stop will be projected inwardly to 100 stop the key in the proper position.

105 What I claim is as follows, but modifications may be made in carrying out the invention shown in the drawings and in the above particularly described form thereof within 110 the purview of the invention as defined by the annexed claims.

I claim:

1. A key operated combination lock comprising a casing, several flat tumblers therein, each having a peripheral notch, means to operate one of the tumblers with a key, means to retract the lock bolt when the tumbler notches are aligned, means to operate one of the tumblers from the key tumbler, 115 a flat spring on another tumbler to operate a third tumbler, and means on the key tumbler to extend said lock bolt by a reverse movement of the key.

120 2. A key operated combination lock comprising a casing, several flat tumblers therein, each having a peripheral notch, means to operate one of the tumblers with a key, frictional means whereby all the tumblers may be set by the operation of the key, means to 125 130

retract the lock bolt when the tumbler notches are aligned, and means on the key tumbler to extend said lock bolt by a reverse movement of said key.

- 5 3. A key operated combination lock, comprising a lock body, a hasp adapted to be locked therein, a key for operating the lock

and a detachable ring carrying a series of movable stops for determining the position of the key in operating the lock. 10

In testimony whereof I have hereunto set my hand this 30th day of October A. D. 1924.

MARKO TUDOROV.
